SELF-PROPELLED WATER CRAFT

Melvin T. Dodd, P.O. Box 332, Malakoff, Tex.

Filed Aug. 1, 1960, Ser. No. 61,578

Term of patent 14 years

(Cl. D71—1)

Fig. 1

Fig. 2

Fig. 3

Fig. 4

Fig. 5

FIG. 1 is a rear perspective view of a self-propelled watercraft showing my new design,

FIG. 2 is a side elevational view,

FIG. 3 is a front elevational view,

FIG. 4 is a top plan view, and

FIG. 5 is a bottom plan view.

The dominant features of my new design are shown in full lines.

I claim:

The ornamental design for a self-propelled water-craft, as shown and described.
